IMAGE REJECTOR CIRCUIT FOR RADIO RECEIVERS

Robert Benjamin Albright, Philadelphia, Pa., assignor to Philco Radio and Television Corporation, Philadelphia, Pa., a corporation of Delaware

Application January 5, 1938, Serial No. 183,542
In Great Britain January 9, 1937

10 Claims. (Cl. 250--20)

This invention relates to novel means for suppressing or attenuating undesired signals in radio receiving systems and, more particularly, to means for attenuating so-called image signals in radio receivers of the superheterodyne type.

The principal object of the invention is to provide a novel device of this character which may be employed to advantage in a superheterodyne multiband receiver, that is a receiver adapted to receive signals in a plurality of frequency bands, and which device embodies a minimum number of circuit elements and utilizes certain elements in a dual manner.

Another object of this invention is to provide a multiband receiver of the superheterodyne type in which the coil or coils of an unused wave band are employed to attenuate undesired image signals associated with the desired signals in the particular wave band being used, and in which the same coils are used for the transfer of desired signals in their particular bands, thus permitting the coils to serve a dual purpose.

Still another object of the invention is to provide a novel antenna circuit for a radio receiver of this type, which circuit has associated with it the novel image suppression device provided by the invention.

Although the principles of the invention are applicable in any instance where it is desired to attenuate undesired signals and to transfer desired signals substantially unaffected, as stated above, the invention is particularly adapted for use in a superheterodyne multiband radio receiver and, therefore, it will be described herein with particular reference to such specific application.

As is now well known, any superheterodyne receiver is responsive to signals of two different frequencies which represent the sum and difference, respectively, of the oscillator frequency and the intermediate frequency of the receiver. To a lesser extent, the receiver is also responsive to signals whose frequencies represent the sum and difference, respectively, of the intermediate frequency and harmonics of the oscillator frequency. One of the signals to which the receiver is responsive is commonly known as the image signal. The presence of the image signal is particularly undesirable in certain instances, for example in the reception of signals in the long wave band, that is signals having a frequency in the frequency range between 150 and 350 kilocycles, since the image signals corresponding thereto lie in the standard broadcast band which extends from 550 kilocycles to 1600 kilocycles within

which there are present signals emanating from powerful transmitting stations. For example, if the intermediate frequency of a receiver is 450 kilocycles, the image frequency range corresponding to signals in the long wave band will extend from 750 kilocycles to 1250 kilocycles. Therefore, in order to receive signals in the long wave band efficiently, it is necessary that the strong image signals present in the broadcast band be effectively attenuated.

The present invention accomplishes this desired result by providing a signal transfer path between the antenna and first tuned circuit which path includes an impedance in shunt across the path which impedance has a high value and therefore good transfer characteristics for desired signals but a low value and therefore poor transfer characteristics for the undesired signals. Moreover, the invention utilizes for this purpose certain elements which are used for reception of signals in the broadcast band, thus causing such elements to serve a dual purpose. In this manner, the desired image suppression is effected employing a minimum number of parts or elements.

Other objects and features of the invention will be apparent from consideration of the drawing and specification. The single figure of the drawing is a diagrammatic illustration of one embodiment of the invention.

Referring now to the drawing, there is shown a multi-band radio receiver which is adapted to receive signals in the usual frequency bands, viz., the long wave band, the broadcast band and the short wave band. To this end, there are provided three tuning coils L_1 , L_2 and L_3 which are respectively designed to be tuned to signals in the long wave band, the broadcast band and the short wave band by means of the tuning condenser C_t and the padding condensers C_{p1} , C_{p2} and C_{p3} associated respectively with the coils L_1 , L_2 and L_3 . By means of the three-position switch S_1 , any one of these coils may be selected to adapt the receiver for reception of signals in a particular frequency band, as will be well understood. As illustrated, the selectable contacts 1, 2 and 3 of the switch S_1 are connected respectively to the coils L_1 , L_2 and L_3 . Preferably there should be some coupling between L_1 and L_2 as indicated by M in the figure. Suitable grid bias or automatic volume control bias may be supplied to the grid of the control tube V by means of the isolating resistance R connected to the common point of L_1 , L_2 and L_3 as shown.

Signals may be supplied to the several tuned

- circuits either from a conventional high impedance antenna A or from a low impedance source such as the transmission line T. L. which may be connected to an associated antenna as well understood. When it is desired to receive signals from the antenna A, the antenna may be connected to the terminal 4 and the signal transfer will then take place through the capacity coupling comprising condensers C₁, C₂ and C₃. When it is desired to receive signals from the transmission line T. L., the line may be connected to the terminals 5 and 6, which are connected to the primary winding P of transformer T, the mid-point of the primary winding being connected 15 to ground so as to balance the transmission line. Secondary S of the transformer has one end connected to ground and its other end connected to a point between condensers C₂ and C₃ so that the transformer secondary is shunted about the 20 condenser C₃. The signal transfer takes place through the coupling transformer T which builds up a signal across the condenser C₃ from whence the signal is supplied to the selected tuned circuit.
- 25 The wave band switch S₁ is connected to the input element of a vacuum tube V so that the switch is adapted to connect the selected tuned switch to the said input element. The tube V circuit may be a conventional detector-oscillator or it 30 may be a conventional tube of the mixer type. In any case, there will be associated with the tube V and oscillator O having a tuning condenser C_t, which condenser may be ganged with the tuning condenser C_t for simultaneous operation 35 of the two tuning condensers, as indicated by the broken-line representation. It will be understood that the oscillator is a conventional device which requires no further illustration than the diagrammatic representation of the drawing.
- 40 The output of the tube V may be supplied to any suitable utilization means such as the intermediate frequency amplifier of a conventional superheterodyne radio receiver.

In accordance with the present invention, there 45 is provided a second switch S₂ which may be a three-position switch similar to the switch S₁ as illustrated, although only one position of switch S₂ is utilized in the manner to be presently described. Preferably, the switch S₁ and S₂ are 50 ganged or connected together for simultaneous operation as indicated by the broken-line representation. The stationary contact 1 of switch S₂ is connected to the stationary contact 2 of switch S₁ as illustrated. A condenser C₄ has one 55 side connected to the movable arm of the switch S₂ and its other side connected to ground. It will be seen, therefore, that when the switch S₂ is in its position 1, the coil L₂ is connected to the condenser C₄. When the switch S₂ is in either 60 of its positions 2 and 3, however, it is ineffective since its contacts 2 and 3 are "dead" contacts.

Suppose now that it is desired to receive signals in the long wave band, as described above, the switch S₁ will be thrown to its position 1 so as 65 to select the long wave band coil L₁. At the same time, the switch S₂ will, of course, be thrown to its position 1, thus connecting the condenser C₄ to the broadcast band coil L₂. The coil L₁ is now energized by the signal across the condensers C₂ and C₃. It will be noted, however, that the 70 series circuit comprising coil L₂ and condenser C₄ is placed in shunt relation with the condensers C₂ and C₃. Remembering that the coils L₁ and L₂ are adapted respectively to be tuned to receive 75 signals in the long wave band and the broadcast

band by means of the common tuning condenser C_t, it will now be apparent that the condenser C₄ may be designed in such relation to the coil L₂ that the series circuit L₂C₄ may be made to attenuate image signals in the broadcast band. By designing the condenser C₄ so that it has a capacity equal to about one-half the maximum capacity of the tuning condenser C_t, the series circuit L₂C₄ may be made resonant at a frequency 10 in the lower end of the image frequency band 15 associated with the long wave band. For example, the resonant frequency may be in the neighborhood of 750 k. c. At low frequencies corresponding to desired signals in the low wave band (i. e., 150-350 k. c.), the series circuit will have a very high capacitive reactance and hence 20 will not deleteriously effect the transfer of desired signals. With respect to image signals, however, the series circuit will substantially completely suppress those signals having a frequency in the lower part of the image frequency range since, 25 for signals of such frequencies (i. e., near the resonant frequency of L₂C₄), the impedance of the series circuit L₂C₄ is very small. For undesired signals in the high end of the image frequency band, the impedance of condensers C₂ and C₃ will be small and will prevent the transfer 30 of such signals to a considerable extent. However, by coupling L₁ and L₂ slightly in accordance with the invention, further suppression of undesired image signals in the high part of the image signal band may be had. This obtains from the fact that for these higher image frequencies, the image frequency current in L₂ will induce a 35 voltage in L₁ which will oppose the undesired image signal in that circuit. Complete balancing out may be obtained at one frequency, for example, the middle of the image band, and for the remainder of the band the two signals will oppose 40 one another and nearly completely balance out. 45

For reception of signals in the broadcast band, the switches S₁ and S₂ are moved to position 2 and the circuit L₂-C_t may be tuned to the desired signal in the broadcast band in the normal manner. Reception of signals in the short wave band 45 likewise obtains by moving S₁ and S₂ to position 3. It will be understood of course that the padding condensers C_{p1}, C_{p2} and C_{p3} will be adjusted 50 so that the tuning condenser C_t will "track" in each band. 55

Generally speaking, it has been found that by using the circuit of the invention as above described, it is necessary to provide only two tuning condensers instead of three such condensers as used heretofore to obtain satisfactory image signal attenuation. Thus, in this respect also the invention simplifies the radio receiver and effects economy in the manufacture thereof. 60

In a specific embodiment of the invention, the following values were found to be satisfactory. 60 The coil L₁ may have an inductance of 2580 microhenries. The coil L₂ may have an inductance of 221 microhenries. The coil L₃ may have an inductance of 1.9 microhenries. The tuning condenser C_t may be of sufficient capacity to tune 65 these coils over the above-mentioned frequency bands. The condensers C₁, C₂ and C₃ may each have a capacity of .01 microfarad. The tube V may be of any suitable type such as the 6A7G frequency converter, or a simple tetrode. The 70 intermediate frequency of the radio receiver may be 451 kilocycles. 75

The coils L₁ and L₂ may be wound on the same form. In the above specific embodiment, L₁ comprises 365 turns of 3-40 Litzendraht wire and L₂

comprises 82 turns of 7-41 Litzendraht wire, both windings being of the universal type and in the same direction. The coils were wound on a $\frac{1}{16}$ " form and spaced $\frac{5}{8}$ ". The beginnings of each winding were connected together and to C_2 . The end of the winding L_1 was connected to C_1 and the end of the winding L_2 to C_4 , by means of the switches S_1 and S_2 , respectively.

While the invention has been described with respect to a single embodiment thereof, it will be understood that various modifications may be made as will be apparent to those skilled in the art and consequently the invention is not limited to the specific form shown in the figure.

15 I claim:

1. In a multiband superheterodyne radio receiver, a signal channel, a tuning condenser, a coil tunable to a desired signal in one wave band by said condenser, a second coil tunable to a desired signal in a different wave band by said condenser, each of said coils having one end connected in the signal channel, a wave band switch for connecting the other end of one coil in the signal channel for transferring desired signals in its wave band and for alternatively connecting the other end of the second coil in the signal channel for the transfer of desired signals in the second wave band, a condenser of predetermined capacity relative to the inductance of one of said coils, and means including a switch for serially connecting said last-mentioned coil and condenser in shunt with the signal channel to suppress undesired signals associated with the desired signals upon operation of said wave band switch to connect the first-mentioned coil in the signal channel.

2. In a multiband superheterodyne radio receiver, a signal channel, a tuning condenser, a coil tunable to a desired signal in one wave band by said condenser, a second coil tunable to a desired signal in a different wave band by said condenser, each of said coils having one end connected in the signal channel, a wave band switch for connecting the other end of one coil in the signal channel for transferring desired signals in its wave band and for alternatively connecting the other end of the second coil in the signal channel for the transfer of desired signals in the second wave band, a condenser of predetermined capacity relative to the inductance of one of said coils, and means including a switch for serially connecting said last-mentioned coil and condenser in shunt with the signal channel to suppress undesired signals associated with the desired signals upon operation of said wave band switch to connect the first-mentioned coil in the signal channel, said last-mentioned condenser having a value between the minimum and maximum values of said tuning condenser.

3. In a multiband superheterodyne radio receiver, a source of signals, a tuning condenser, a plurality of coils, each of said coils being tunable by said tuning condenser to transfer desired signals in different wave bands, a common connection between one end of each of said coils, connections for transferring signals from said source to said common connection, an amplifier, means for connecting the tuning condenser in shunt with the input circuit of said amplifier, a wave band switch for alternatively connecting the other ends of said coils to the tuning condenser to transfer desired signals in the respective wave bands, a condenser of predetermined capacity relative to the inductance of one of said

coils, and switch means for serially connecting last-mentioned coil and condenser in a shunt path across said signal source upon operation of said wave band switch to connect another of said coils in the signal channel, the said series-connected elements in said shunt path being resonant to undesired signals associated with the desired signals transferred by said other coil.

4. In a multiband superheterodyne radio receiver, a source of signals, a tuning condenser, a plurality of coils, each of said coils being tunable by said tuning condenser to transfer desired signals in different wave bands, there being some mutual coupling between said coils, a common connection between one end of each of said coils, connections for transferring signals from said source to said common connection, an amplifier, means for connecting the tuning condenser in shunt with the input circuit of said amplifier, a wave band switch for alternatively connecting the other ends of said coils to the tuning condenser to transfer desired signals in the respective wave bands, a condenser of predetermined capacity relative to the inductance of one of said coils, and switch means for serially connecting said last-mentioned coil and condenser in a shunt path across said signal source upon operation of said wave band switch to connect another of said coils in the signal channel, the said series-connected elements in said shunt path being resonant to undesired signals associated with the desired signals transferred by said other coil.

5. In a multiband radio receiver, a source of signals, a vacuum tube having at least a cathode, a control grid, and an anode, a tuning condenser connected between said cathode and said control grid, a plurality of coils, each of said coils being tunable by said tuning condenser to signals in different wave bands, a capacitor of predetermined capacity relative to the inductance of one of said coils, and switching means for connecting another of said coils serially between said signal source and said control grid, while simultaneously connecting said one coil and said capacitor in series across said signal source.

6. In a multiband radio receiver, a source of signals, said source having a high potential side and a low potential side, a vacuum tube having at least a cathode, anode and control grid, a tuning condenser connected between said cathode and said control grid, a connection between the low potential side of said signal source and said cathode, a first coil capable of being tuned over a certain frequency band by said condenser, a second coil capable of being tuned over a second frequency band by said condenser, switching means for selectively connecting either one of said coils serially between the high potential side of said signal source and said control grid, whereby the selected coil may be tuned to series resonance by said tuning condenser, a capacitor having a predetermined capacity relative to the inductance of said second coil, and additional switching means operative when said first coil is switched into circuit for connecting said second coil and said capacitor in series across said signal source.

7. In a multiband superheterodyne radio receiver, a source of signals, said source having a high potential side and a low potential side, a vacuum tube having at least a cathode, anode and control grid, a tuning condenser connected between said cathode and said control grid, a connection between the low potential side of said signal source and said cathode, a first coil capa-

- ble of being tuned over a certain frequency band by said condenser, a second coil capable of being tuned over a second frequency band by said condenser, switching means for selectively connecting either one of said coils serially between the high potential side of said signal source and said control grid, whereby the selected coil may be tuned to series resonance by said tuning condenser, a capacitor having a predetermined capacity relative to the inductance of said second coil, and additional switching means operative when said first coil is switched into circuit for connecting said second coil and said capacitor in series across said signal source, said second coil and said capacitor being adjusted to give series resonance at some point in the image frequency band associated with the band covered by said first coil.
8. In a multiband radio receiver, a source of signals, said source having a high potential side and a low potential side, a vacuum tube having at least a cathode, anode and control grid, a tuning condenser connected between said cathode and said control grid, a connection between the low potential side of said signal source and said cathode, a first coil capable of being tuned over a certain frequency band by said condenser, a second coil capable of being tuned over a second frequency band by said condenser, said coils being inductively coupled, switching means for selectively connecting either one of said coils serially between the high potential side of said signal source and said control grid, whereby the selected coil may be tuned to series resonance by said tuning condenser, a capacitor having a predetermined capacity relative to the inductance of said second coil, and additional switching means operative when said first coil is switched into circuit for connecting said second coil and said capacitor in series across said signal source.

9. In a multiband radio receiver, a source of signals, said source having a high potential side and a low potential side, signal transfer means having a high potential side and a low potential side, a tuning condenser connected between the high and low potential sides of said transfer means, a connection between the low potential side of said source and the low potential side of said transfer means, a plurality of coils, means connecting one end of each coil to the high potential side of said source, switching means for selectively connecting the other ends of said coils to the high potential side of said transfer means, the said coils being tunable respectively by said condenser over different frequency bands, a capacitor having a predetermined capacity relative to the inductance of one of said coils, and means for serially connecting said capacitor and said one coil in shunt with said source upon operation of said switching means to connect another of said coils to said transfer means.

10. In a multiband radio receiver, a source of signals, signal transfer means, a tuning condenser connected across said transfer means, a connection between one side of said source and one side of said transfer means, a plurality of coils, means connecting one end of each coil to the other side of said source, switching means for selectively connecting the other ends of said coils to the other side of said transfer means, the said coils being tunable respectively by said condenser over different frequency bands, a capacitor having a predetermined capacity relative to the inductance of one of said coils, and means for serially connecting said capacitor and said one coil in shunt with said source upon operation of said switching means to connect another of said coils to said transfer means.

ROBERT BENJAMIN ALBRIGHT. 40
